ABSTRACT

The alternating current signal to be demodulated is applied to a resistive voltage divider which provides two alternating current voltages. An NPN transistor and a PNP transistor are connected to the voltage divider and are alternately rendered conductive during half cycles of the alternating current voltages so that one transistor passes alternate half cycles of one voltage and the other transistor passes the other alternate half cycles of the other voltage. The passed voltages are combined to provide a full wave demodulated output corresponding in polarity to the phase of the alternating current voltage.

FULL WAVE PHASE SENSITIVE DEMODULATORS

BACKGROUND OF THE INVENTION

1. Field of the Invention

The present invention relates to phase sensitive demodulators and, more particular, to a phase sensitive demodulator for providing a full wave demodulated signal.

2. Description of the Prior Art

Heretofore, full wave phase sensitive demodulators used center-tapped transformers with similar type transistors. The transformers, because they are reactive, caused the demodulator to have a slow response time and frequency limitations. The similar type transistors required a a separate biasing voltage for each transistor.

The device of the present invention uses a resistive voltage divider to improve response time and avoid frequency limitations. The use of transistors of different types which may be controlled by a single biasing voltage reduces power consumption.

SUMMARY OF THE INVENTION

A phase sensitive demodulator for demodulating an alternating current signal comprising means for dividing the alternating current signal into two alternating current voltages and having a connection common to both voltages. An output terminal is connected to the common connection of the dividing means. NPN and PNP type transistors are connected between the dividing means and the second output terminal. The transistors are alternately rendered conducting in alternate half cycles of the voltages and pass one of the voltages from the dividing means to the output terminals in alternate half cycles when one transistor conducts and for passing the other voltage from the dividing means to the output terminals in the other alternate half cycle when the other transistor conducts to provide a demodulated output across the output terminals corresponding in polarity to the phase of the alternating current signal.

One object of the present invention is to provide a phase sensitive demodulator which demodulates an alternating current signal and provides a full wave demodulated output.

Another object of the present invention is to divide an alternating current signal to provide two signals so that half cycles of the two signals may be combined to provide a full wave demodulated signal.

Another object of the present invention is to provide a full wave phase sensitive demodulator having no reactive elements so as to have an unlimited frequency response and a fast response time.

Another object of the present invention is to use an NPN transistor and a PNP transistor controlled by a simple alternating current bias phase related to an alternating current signal to be demodulated.

The foregoing and other objects and advantages of the invention will appear more fully hereinafter from a consideration of the detailed description which follows, taken together with the accompanying drawings wherein one embodiment of the invention is illustrated by way of example. It is to be expressly understood, however, that the drawings are for illustration purposes only and are not to be construed as defining the limits of the invention.

DESCRIPTION OF THE DRAWINGS

FIG. 1 shows a schematic diagram of a full wave phase sensitive demodulator constructed in accordance with the present invention.

FIGS. 2A through 2E are diagrammatic representations of voltages occurring during operation of the phase sensitive demodulator shown in FIG. 1.

DESCRIPTION OF THE INVENTION

Referring to FIG. 1, a phase sensitive demodulator constructed according to the invention, is shown as comprising a

resistive voltage divider including resistor 5 and 6 having a common connection 8 and connected in series across a signal source which provides an alternating current signal source E_1 , shown in FIG. 2A, to be demodulated. Resistors 5, 6 provide two alternating current voltage E_5 and E_6 in phase with signal E_1 .

In FIG. 1, an output terminal 13 is connected to common connection 8. A PNP transistor 12 has a collector 14 connected to a terminal 2 and an emitter 16 connected to a second output terminal 17. An NPN transistor 22 has a collector 24 connected to a terminal 3 and an emitter 26 connected to an output terminal 17. Transistor 12 and 22 are alternately saturated and rendered conducting by a biasing voltage E_4 , as shown in FIG. 2C, applied across a terminal 33 connected to emitters 16 and 26 of transistors 12 and 22, respectively, and a terminal 34 connected to a common connection between biasing resistors 41 and 43 connected to bases 20 and 30 of transistors 12 and 22, respectively. Biasing voltage E_4 is phase related to signal E_1 and as shown in FIGS. 2C and 2A, E_4 is in phase with signal E_1 .

Transistor 12 is saturated and conducts during positive half cycles of bias voltage E_4 . The low collector-emitter resistance of transistor 12 results in an insignificant voltage drop and positive half cycles of voltages E_5 across resistor 5 are essentially provided to terminals 13, 17. Transistor 22 saturates and conducts during negative half cycles of bias voltage E_4 . The low collector-emitter resistance of transistor 22 results in an insignificant voltage drop and negative half cycles of voltage E_6 across resistor 6 are essentially provided to terminals 13, 17. Due to the connection of transistor 22, resistor 6 and terminals 13 and 17, the negative half cycles of voltage E_6 are inverted. Thus output E_2 is composed essentially of the positive half-cycles of voltage E_5 and the inverted negative half-cycles of voltage E_6 .

When signal E_1 and bias E_4 are in phase, transistor 22 has a forward current when conducting from collector 24 to emitter 26 due to voltage E_6 . Transistor 12, when conducting, has a reverse current from collector 18 to emitter 19 due to voltage E_5 . Similarly transistor 22 experiences a reverse current due to voltage E_6 when signal E_1 is 180° out-of-phase with bias E_4 . Since a reverse current will occur during operation of demodulator 1, care should be taken that the reverse current does not exceed the reverse current capability of the particular type of transistor used.

The reverse resistance between each emitter and collector is approximately equal to the forward resistance between each emitter and collector due to the saturation of transistor 12 or 22 by bias E_4 .

Demodulator 1 may be operated when signal E_1 is 180° out-of-phase with bias E_4 such as shown in FIG. 2D. Output E_2 will then be a negative full wave output shown in FIG. 2E.

The device of the present invention as heretofore described is a full wave phase sensitive demodulator in which an alternating current signal is divided into two alternating current voltages and half cycles of the two alternating current voltages are combined to provide a full wave demodulated output. The device of the present invention is a full wave phase sensitive demodulator using no reactive parts and having an unlimited frequency response and a fast response time.

What is claimed is:

1. A phase sensitive demodulator for converting an alternating current signal to a demodulated output, comprising:
means for dividing the alternating current signal into two alternating current voltages;
a terminal common to both voltages;
an output terminal connected to the common terminal;
a second output terminal;
a pair of transistors having collector elements connected through the dividing means to the common terminal, emitter elements connected to the second output terminal and base elements;
means including an alternating current bias phase related to the two alternating current voltages connected across the

emitter and base of each transistor for controlling conduction of the transistors; and the controlling means alternately rendering the transistors conducting in half cycles of the voltages providing an output across the output terminals in the alternate half cycles when one transistor conducts and for providing an output

across the output terminals in the other alternate half cycles when the other transistor conducts to provide a demodulated output across the output terminals corresponding in polarity to the phase of the alternating current signal.
